UNITED STATES PATENT OFFICE.

GEORGE E. MARLATT, OF PASADENA, CALIFORNIA.

TYPOGRAPHICAL MACHINE.

Application filed October 5, 1926. Serial No. 139,720.

My invention relates to typographical machines of the linotype class in which circulating matrices are released by keyboard means from a storage magazine and assembled in a line in the order of their release, the assembled line transferred to a position in front of a mold in which a cast of type metal is made against the line of matrices, and the matrices then returned to their individual channels in the magazine from which they were released.

The main purpose of my invention herein disclosed is to provide a multiple-magazine machine in which the magazines are of simple construction and adequate capacity and may be readily moved to and from operative position for selective use. Incidentally, I provide certain distributor improvements, keyboard improvements, and other minor and contributing improvements to co-operate with the magazine system, all of which will be fully explained as the description progresses.

In the accompanying drawings, the keyboard position is the front of the machine, and

Fig. 1 is a right-hand side elevation.

Fig. 2 is a view from the front on the line 2—2 of Fig. 1.

Fig. 3 is a view from the front on the line 3—3 of Fig. 1.

Fig. 4 is an enlargement of a portion of Fig. 1.

Fig. 5 is similar to Fig. 4, but with certain parts in shifted position.

Fig. 6 is a fragmentary plan view of the left-hand side of a keyboard having a certain number of keys to co-operate with a magazine having a corresponding number of channels.

Fig. 7 is a fragmentary plan view of the right-hand side of a keyboard having fewer keys than represented in Fig. 6 and designed to co-operate with a magazine having a corresponding number of channels.

Fig. 8 is a left-hand view on the line 8—9 of Figs. 1 and 4.

Fig. 9 is a right-hand view on the line 8—9 of Figs. 1 and 4, but with certain parts in shifted position.

Fig. 10 is an enlargement of the upper or distributor portion of Fig. 1.

Fig. 11 is a section through a part of Fig. 10.

Fig. 12 is a view on the line 12—12 of Fig. 10.

Magazine system.—As shown in the drawings, the magazines A are five in number, but a greater or smaller number may be employed to meet various requirements. The 60 magazines are as usual provided with opposed-groove channels in which the matrices are stored in columns according to character. The magazines are shiftable in the manner of U. S. Patent No. 1,136,569 (April 20, 65 1915), but in the present instance as distinguished from said patent, the magazines differ one from another as to the number and spacing of their channels, and means is provided for releasing the matrices from the 70 magazines as thus differentiated and are, divided midway of their width (Fig. 3), hence there are two columns or stacks of magazine halves, one column being supported on a left-hand frame B and the other column on 75 a right-hand frame C. These frames are supported from a rock-shaft D having a fore and aft bearing in the main supporting frame E which is rigidly secured to the machine base F. The rock-shaft D carries 80 front and rear rocking arms G and on the ends of these arms the frames B and C are supported by means of links H. At opposite ends of the links H a hinged connection is established by means of rods I and J, the rods 85 I also serving to space apart the front and rear rocking arms G and the rods J similarly spacing apart the magazine direct supports B. Additional rigidity for the frames is obtained by means of spacing rods R, R¹, 90 R². A central frame member K provides additional support for the rock-shaft D and is shaped to receive and guide the parallel portions of the magazine supports B and C, the sides of which bear against suitable anti-friction rollers L and M. Similarly, the forward surfaces of the frames B bear against anti-friction rollers N. Tie-rods O brace the central frame member K from a column-like portion P of the machine frame. The lower 95 extensions of the movable supports B, C are guided between the rock-shaft D and guiding plates E¹ secured to opposite sides of the main frame E. As thus supported the two columns of magazine halves have a reciprocating movement in parallel paths when the supporting shaft D is rocked. When the magazine halves are in position mid-way of their possible movement, as in Fig. 2, the middle magazine indicates operative position, hence any pair of magazine halves brought to such position become the opera-

tive magazine. For example, the top magazine-half of one column is the mate of the bottom magazine-half of the other column when the two halves are brought to operative position in relation to the usual assembler throat Q. In both Figs. 1 and 2 the middle magazine is shown in operative position. In Fig. 3 the second magazine-half from the top of the right-hand column and the one second from the bottom of the left-hand column are in operative position. The exponent numbers employed with the reference character A in Fig. 3 indicate how the magazine halves match when shifted to operative position. The halves 1-2-3 reading downward from the center of the left-hand stack match successively the halves 1-2-3 reading upward from the center of the right-hand stack; the same is true of the halves 1-4-3 reading in an opposite direction in the respective stacks.

Each magazine-half is provided with front and rear cross bars S on top and similar bars T beneath, there being a tongue-and-groove connection between the bars on top of one magazine and those beneath the magazine next above. The ends of the bars T project beyond the edge of the magazine to which they are secured and rest on shoulders U formed in the supporting frames B, C. Top magazines of each column have a similar tongue-and-groove engagement with the horizontal arms of right-angled levers V which are pivoted on a shaft W and are capable of a slight movement under control of cams X on opposite ends of a shaft Y bearing in the frames B or C. When these cams are turned by moving a handle Z outwardly as at the right of Fig. 3, the horizontal arm of the levers V is thereby tilted and lifts first the top magazine and then each succeeding magazine according to the extent of movement of the cams X, each magazine being suspended from the one next above by reason of the tongue-and-groove connection described. The lower most magazine thus suspended is freed of the weight of the magazines thereabove and may therefore be moved edgewise to or from its column position, as shown in dotted lines in Fig. 3. By shifting the supporting frames to the appropriate position any magazine-half may be thus removed to a position above and resting upon the opposite magazine column and then lifted from the machine and another magazine substituted therefor. By reversing the position of the tilt-frame the other half of the magazine may be similarly removed from its column.

As a means for holding the magazine columns in any selected operative or removal position, I secure to the end of the rock-shaft D a segmental rim D¹ having a series of positioning notches D² any one of which notches may be brought to a position above

the rock-shaft and there engaged by a latching rod D³. At its lower end this latching rod is confined in a groove D⁴ and is movable longitudinally for the purpose of locking or freeing the notched rim D¹. The latching rod D³ is additionally guided in an extension K¹ of the central frame K. It is provided with a clearance notch D⁵ through which the rim D¹ may turn when the latching rod is moved downwardly a proper distance. For the purpose of such movement it is secured to a cross member D⁶ carried by a pair of substantially vertical rods D⁷ disposed at opposite sides of the machine. These rods D⁷ have a slight longitudinal movement incidental to the movement of a pair of swinging brackets D⁸, the further functions of which is hereinafter explained. The brackets D⁸ are pivotally secured to the assembler entrance throat Q (Fig. 1) by means of hinge pins Q¹ and when swung outwardly as shown in broken lines in Fig. 1 the latching rod D³ is thereby forced downward and the rim D¹ may turn through the clearance notch D⁵ and with the return movement of the rod D³ be latched in a selected position according to the magazine selected for use. The lowermost notches D² are for use when moving the bottom magazine of one column to a position above the top magazine of the other column, for the purpose of removing the magazine as explained. The manner of controlling the movement of the magazine columns between one and another locked position is hereinafter explained.

Keyboard system.—The magazines A are intended to differ one from another in regard to the number of their channels. For example, a magazine intended for large matrices such as 24-point may have only 60 channels; a magazine for 18 point matrices may have 90 channels, and a magazine for very small matrices may have 120 channels. Hence it is desirable that there be associated with each magazine when in use a keyboard having keys equal in number to the channels in the magazine in use. With this purpose in view, I provide four keyboards (1, 2, 3, 4) mounted in common end members 5 rotatable with a shaft 6 for the purpose of moving a selected keyboard to operative position. The shaft 6 bears at opposite sides of the keyboard group in side arms 10 secured to a pivot shaft 11 with a bearing in the machine base F. When in normal position the keyboards cannot be rotated because of the interfering escapement reeds 20. It is therefore necessary to lower the keyboards as shown in dotted lines in Fig. 1 before they can be rotated. For the purpose of such movement to and from normal position they are balanced by means of a compression spring 13 held in position on a rod 14 having a bearing in a vertical angle-portion

10^a of the side arm 10, and slidable therein when the spring is compressed. The other end of the spring rod is secured by means of a link 16 in a projection 17 from the 5 side of an arm 18 pivoted with a shaft 15 bearing in the machine frame E. The arm 18 and the arm 10 are spaced apart by the link 16, and the relative positions of the pivotal points of these two arms is such 10 that when they are lowered to the position shown in dotted lines the spring 13 is compressed and supports the weight of the keyboard group in common with two additional springs 19 and 21. The tension of 15 the springs 19 and 21 may be regulated by means of a sleeve 22 on the spring rod D⁷, the sleeve being threaded into the cross member D⁶ hereinbefore described. The springs 19 and 21 may be in duplicate at opposite sides of the machine and are so shown in Fig. 2. The brackets D⁸ carry arms D⁹ which support a keyboard tray 23 and copyholder 24. When the keyboards are in normal position a latch 25 carried by the 20 arm 18 engages a notch in the right-hand arm D⁹ and thus holds the keyboards in position. Before they may be lowered the keyboard tray 23 must be swung out as illustrated and this movement slightly compresses the spring 19 against an eye-bolt 24 carried by the arm 18, thus starting the 25 downward movement of the keyboard group regardless of the stronger spring 13; when the tray 23 is returned to normal position 30 the tension of the spring 19 is gradually lessened and the stronger spring 13 raises the keyboard group and the latch 25 enters its notch. The spring rod D⁷ slides in the eye-bolt 24 and as the tension of the spring 19 35 increases, that of the spring 21 decreases, with the condition reversed as the keyboards rise.

Associated with each keyboard is a projecting stud 26, and when the keyboards are 40 in normal position one of these studs engages a notch 27 in the end of the arm 18, thus preventing any rotary movement of the keyboards. As the keyboards are lowered the stud 26 gradually recedes from the notch 45 27 and when entirely free thereof the group of keyboards may be rotated to bring a selected one to operative position. The return movement of the group then causes another stud 26 to enter the notch 27.

50 When the keyboards are rotated a gear 7 on the shaft 6 moves a centrally pivoted arm 8 about its pivot 9, the direction of this movement depending on the direction in which the keyboards are rotated.

55 *Inter-control between magazine system and keyboard system.*—In order that a keyboard having a given number of keys may be brought to operative position in time with a magazine having a corresponding number of channels, I provide as follows: A con-

necting rod 28 is hinge-connected at its upper end with the shaft W and at its lower end is hinge-connected with the centrally-pivoted arm 8 at a point central with the pivot point 11 of the keyboard arm 70 10; therefore when the keyboard system is lowered, no movement is imparted to the connecting rod 28. But when the keyboards are rotated the gear 7 moves the segment-arm 8 and causes the magazine columns to 75 move a related distance in a direction depending on the direction of rotation of the keyboards. For example, if the keyboards 1 and 3 have 120 keys and (in the right-hand stack) the middle magazine A¹, top magazine A³ and bottom magazine A³ each have 120 channels, a 180-degree rotation of the keyboards from the position shown in Fig. 1, will in one direction cause the lower magazine A³ to move to operative position 80 85 in time with the keyboard 3; and rotation in the other direction will move the top magazine A³ to operative position in time with the same keyboard 3. It will be apparent that if these three magazines each have the 90 same number of channels two keyboards having the same number of keys are required for automatically timing the movement of the magazines and keyboards. But the duplicate keyboard 3 may be dispensed with and the 95 same result obtained by manually moving the lower end of the connecting rod 28 to an appropriate perforation 29 in the arm 8, thus moving the magazines without rotating the keyboards. In such case the end of the 100 rod 28 passes through the selected perforation 29 a sufficient distance to enter a registering perforation in the arm 10, thus securely locking the parts together regardless of any looseness between the 105 gear 6 and the toothed end of the arm 8. Likewise, if a keyboard 2 has 90 keys and a magazine in the position A² has a corresponding number of channels, movement of the keyboard 2 to operative position 110 will move the magazine to correspond; and in similar manner the magazine in the position A³ will move to operative position in time with the keyboard 3. Each time the keyboards are raised to operative position 115 following movement of the magazines, the locking rod D³ engages an appropriate notch D² in the locking member D¹, as hereinbefore explained. The perforations 29 are so arranged that, regardless of the position of the arm 8, one row of the perforations will register with a perforation in the arm 10; hence, regardless of the number of keyboards, and regardless of which keyboard is 120 in use, a magazine in any position in its column may be manually brought to operative position without rotating the keyboards, provided the number of keys corresponds with the number of channels; but it is always necessary to swing the tray 23 for 125 130

ward in order to move the latching rod D³ so that the magazines may be moved, whether direct-manually or otherwise.

The escapement actuating reeds 20 are equal in number to the maximum number of channels in a magazine and the corresponding number of keys on a keyboard, and when a magazine of fewer channels is in use certain of the reeds 20 are eliminated and the remaining reeds respaced apart to correspond with the spacing of the reduced number of magazine channels and keyboard keys. This is accomplished in manner as follows: The reeds 20 are guided and spaced apart in notches 30 in a plate 31 fitting in grooves 32 in the facing sides of the brackets D⁸. In the proportion selected for illustration each fourth notch (30°) is deeper than the remaining notches. When employing the reeds in reduced number, every fourth reed is moved forward into its notch to a non-operative position in front of the escapements 33. For this and other purposes the reeds are offset as at 20^a and their upper ends 20^b are guided in notches 34 in a plate 35, except that every fourth reed is guided in a perforation 36. This plate 35 is supported on posts 36 secured near opposite ends of the lower plate 31. Outside of each post 36 an arm 37 is secured to a shaft 38 mounted in the posts 36. A keeper plate 39 engages a groove 40 in the plate 35 and at each end is confined in grooves 41 in the arms 37; thus the plate 35 has a horizontal movement when the arms 37 are moved with the rocking of the shaft 38. When this movement occurs in a forward direction those reeds which are guided in the perforations 36 are moved forward in their notches 30^a in the lower plate 31; and the upper or crank ends 20^b of the reeds are respaced according to the spacing of the open ends of the diagonal notches 34. With the plate 35 in the position shown in Fig. 6 all of the reeds are operative; as shown in Fig. 5 every fourth reed is inoperative and the remaining reeds are respaced to co-operate with the escapements of a magazine having a reduced number of channels.

In order that the movement of the spacing plate 35 may occur automatically with the movement of the magazines, I provide as follows: To the shaft 38 is secured a pair of arms 42, to each of which is pivoted an arm 43. A stud 44 projects from each edge of those magazines having a reduced number of channels, and when the brackets D⁸ are returned to operative position following a magazine shift, the upper end of the arms 43 will contact with the studs 44, forcing the arms 43 downward and moving the plate 35 forward by reason of the connections described. The movement of the arm 43 is resisted by a spring 45, and if the magazine in operative position does not employ the

studs 44 this spring retains the arm in its upward position and all the reeds 20 remain operative.

Since the spacing of the lower ends of the reeds 20 is not changed when a keyboard having a reduced number of keys is in use, it becomes necessary to provide other means for rendering every fourth reed inoperative relative to such keyboard. This is accomplished by bending the key levers 46 as shown in Fig. 7 so that they will engage only the operative reeds, each fourth reed remaining idle between adjoining key levers. Fig. 6 shows all of the reeds operative in connection with a keyboard having a maximum number of keys.

The escapements 33 are similar to those described in my co-pending application No. 139,721, in which certain magazines have escapements and others have merely a perforation in the matrix channels, requiring a raised position of the reeds 20. To accommodate this present invention to such an escapement system, I provide as follows: A pair of levers 47 are secured centrally to a shaft 48 supported in the brackets D⁸. These levers carry a shaft 49 which supports the reeds 20. Arms 50 are pivoted to the levers 47 and those magazines which have the escapements 33 omitted carry studs 51 which force the arms 50 downward when the brackets D⁸ are returned to operative position with such a magazine in use. Thus the levers 47 are rocked with the shaft 48 and the shaft 49 raises the reeds 20 through the openings (not shown) through the magazine floor. When thus raised the reeds rest on a compensating elevation 52 on the key levers 46, a slight manual movement of the tray 23 controlling their position either in front of or above the elevation 52, this movement being insufficient to clear the latch 25. The reeds are guided in a suitable notched or perforated plate 53 near their lower ends.

In said application Serial No. 139,721 it is explained that the escapements 33 are arranged in two alternating series for two sets of matrices in a single magazine. In order that the reeds 20 of this invention may co-operate with such an escapement system the guide plate 31 is arranged to slide in the grooves 30 in facing sides of the bracket D⁸. A slight manual movement of this plate will place the reeds 20 in a selected fore or aft position relative to the escapements for the purpose stated. When the brackets D⁸ are swung forward the plate 31 contacts with a stud 54 and is forced to its rear position, this being the position it should occupy when the reeds are raised as hereinbefore explained when no escapements are employed.

Distributor system and its relation to the magazine system and keyboard system.—The

distributor driving clutch (Figs. 10 and 12) is similar in action to that of my Patent No. 1,389,369. The pulley 55 is provided with a square hub 56 to which are pivoted a pair of clutch members 57 which engage the hub of a gear 58 which meshes with gears on the distributor screws for driving the same. The clutch members 57 are held in resilient engagement with the hub of the gear 58 by means of a split ring 59. In the event of an abnormal condition offering resistance to the distributor screws, the pulley 55 continues to revolve and the clutch members 57 are thrown out of engagement with the hub of the gear 58, whereupon the spring 59 moves across the pivot points 60 of the members 57. The construction differs from that of said Patent No. 1,389,369 chiefly in the substitution of the split ring 59 for the springs of said patent. When the ring 59 is thrown to the position shown in dotted lines (Fig. 12) by reason of an abnormal condition, it strikes and moves a swinging safety lock 62 pivoted in a bracket 61. The swinging end 62' of the lock 62 normally lies between the bracket 61 and an opening 63 through a sliding bracket 64 which supports the shaft 65 upon which the clutch as a whole is supported. Each time the keyboard tray 23 is swung forward preliminary to shifting magazines the slide 64 is moved rearwardly as a result of such movement of the keyboard tray. The connections for causing such movement are a centrally pivoted lever 66, and a rod 67 terminating beneath a shoulder 68 on the assembler-entrance channel Q. The movable tray support D⁹ carries a pawl 69 which engages a shoulder 70 on the rod 67 and is normally held in contact with said shoulder by a spring 71 secured at its opposite ends to the members 67 and D⁹. A stud 73 in the member D⁹ normally lies behind and moves forward with a projection 72 on the rod 67. But if the rod 67 is prevented from moving forward longitudinally by reason of a distributor obstruction, then the stud 73 forces the end of the rod 67 upwardly against the shoulder 68 and the keyboard tray cannot be moved a sufficient distance to permit the magazines to be freed for movement by the latch D³. When an abnormal distributor condition exists the rod 67 cannot move forward because of the fact that the swing end 62' of the lock 62 has been thrown from in front of the opening 63 to the position shown in dotted lines in Fig. 12 and the slide-bracket 64 is as a result locked against movement. It will be understood that the purpose is to prevent a magazine shift while matrices remain on the distributor bar 74 as the result of a distributor stop resulting in the split ring 59 being shifted in position. It may also happen that an attempt be made to shift magazines when the distributor is

running normally but the matrices have not been fully distributed. For such an event I provide as follows: The distributor bar is anchored by means of a bail 75 held in the upper ends of the frame E; hence the distributor bar does not move with the slide-bracket 64. As in my co-pending application Serial No. 139,721 the matrices enter opposed grooves 76 when dropping from the distributor bar. Since the members in which these grooves are formed move with the bracket 64 while the distributor bar remains, the ribs separating the grooves 76 will strike the upper ears of any matrices traveling on the distributor bar when an attempt is made to move the bracket 64 through the connections explained, and as a result the magazines will remain locked against movement until the matrices have been fully distributed. 85

Having thus described my invention and its mode of operation, what I claim as new and desire to secure by Letters Patent, is:

1. The combination, in a typographical machine having a distributor for matrices and a throat through which said matrices pass to assembling position, of a column of matrix magazines differing one from another as to number of their matrix channels according to thickness and number of matrices intended to be accommodated therein, a group of keyboards each having keys equal in number to the channels of one of said magazines and each movable to operative position according to the magazine selected for use, and means for registering a selected magazine in operative relation to said distributor and throat, said means consisting in dividing each of said magazines lengthwise and mounting the halves thereof in separate columns, one column balancing the other column, and one half of each magazine being below operative position while the other half thereof is above operative position. 105

2. A combination as set forth in claim 1, characterized by the fact that the columns of magazine halves therein recited are shiftable by reason of being mounted on a rock-shaft D, and including a notched rim D¹ on said rock-shaft, a lock D³ for said rim, a movable keyboard tray, and an interconnection between said lock and said tray whereby movement of said tray to and from normal position will, respectively, serve to lock said magazine halves in operative position or free them for selective movement. 115

3. A combination as set forth in claim 1, characterized by the fact that the magazine halves therein recited rest one upon another, and including the specified means whereby a selected magazine half may be freed of the weight of an overlying magazine and moved across an opposite column of magazine halves preliminary to removal from the machine. 125

4. In a typographical machine, in combination with a distributor from which matrices are conducted to a delivery throat, pairs of magazines for conducting said matrices from said distributor to said throat, each magazine of each pair being mounted in separate columns of magazines and said columns of magazines being movable in opposite direction to bring a selected pair of magazines in operative relation to said distributor and said delivery throat, means whereby a selected magazine in a selected column may be removed from and inserted in its column without removing 15 overlying magazines, said means comprising levers capable of supporting a selected number of overlying magazines, a cam and handle for controlling said levers, means for supporting a top magazine from said levers, and means for supporting a selected number 20 of underlying magazines from said top magazine.

5. In a typographical machine, in combination, a distributor for matrices, a delivery throat to which said matrices are conducted from said distributor, a column of channeled magazines for selective use in conducting matrices from said distributor to said throat, means for moving said magazines 25 selectively to and from operative position, escapement operating reeds for releasing matrices from said magazines, means for moving said reeds away from said magazines to permit the movement thereof, co-acting means for moving said distributor away from said magazines to permit of their movement, and means whereby an obstruction between said distributor and an operative magazine will prevent the movement 30 of said reeds and hence prevent the movement of said magazines until such obstruction is removed.

6. A combination as set forth in claim 5 including also a group of keyboards for 45 selective use with selected magazines, means for rotating said keyboards for moving a selected one thereof to operative position, and means for preventing the rotation thereof except when conditions permit a corresponding movement of said magazines.

7. In a typographical machine, in combination, a set of channeled magazines differing one from another in regard to the 55 number of channels therein, matrices in the channels of said magazines, escapements, for retaining and releasing said matrices and corresponding in number with the channels of an associated magazine, a series of escapement operating reeds corresponding in number with the number of escapements on a magazine having the maximum number of channels therein, and means for withdrawing certain of said reeds from operative position and respacing the remaining reeds 60 with regard to the number and position of

the escapements on a magazine having a reduced number of channels therein.

8. A combination as set forth in claim 7 including also a set of keyboards for selective use with said magazines and each 70 having key levers corresponding in number with the escapements on an associated magazine, and the specified means for rendering certain of said escapement-operating reeds inoperative relative to said key levers while 75 they are withdrawn from operative position relative to said escapements.

9. A combination as set forth in claim 7 including also means for automatically spacing and respacing the escapement-operating reeds recited therein according to the 80 magazine selected for use.

10. A combination as set forth in claim 7 characterized by the fact that the escapements therein recited differ in form with different magazines, one form of escapement involving a raised position of the escapement operating reeds and the other a lowered position thereof, and including means whereby 85 said reeds are automatically raised and lowered according to the magazine selected for use.

11. In a typographical machine, in combination with a distributor from which matrices are conducted and a delivery throat to 95 which said matrices are conducted and a column of channeled magazines movable for selective use in conducting matrices from one to the other of said elements, a rotatable 100 group of keyboards each of which is associated with an individual magazine when in operative position, and means for causing the rotation of said keyboards to move said column of magazines in order that an associated magazine and keyboard may each 105 move to and from operative position in unison.

12. A combination as set forth in claim 11 characterized by the fact that the column of magazines therein recited comprises magazines divided lengthwise, and that one division of said magazines balances the other division thereof in order to render said column of magazines readily movable.

13. A combination as set forth in claim 11 including also means whereby said column of magazines may be moved independently of said keyboards in order that different magazines in said column may be associated selectively with a single keyboard.

14. A combination as set forth in claim 11 including also escapements on the magazines therein recited for releasing the matrices therefrom and keyboard reeds for actuating said escapements, and the specified means for insuring the movement of said reeds to a non-interfering position before said column of magazines may be moved.

15. A combination as set forth in claim 11 including also the specified means for secur- 130

ing the keyboards therein recited in selective operative positions.

16. In a typographical machine, in combination with magazines each having a different number of column of matrices therein, and a group of keyboards each having keys thereon corresponding in number with the number of columns of matrices in an associated magazine, means for mounting said group of keyboards for rotation about a common center in order that a selected keyboard may be readily moved to operative position for association with a selected magazine.

17. In a typographical machine, in combination with a distributor from which matrices are conducted and a delivery throat to which said matrices are conducted, two columns of magazines for conducting said matrices from

said distributor to said throat, said columns of magazines being supported on individual frames mounted on a common rock-shaft and therefore movable in opposite directions when said shaft is rocked, means for rocking said shaft to bring a selected magazine in each column to operative position, a group of keyboards rotatively mounted for selective employment with a selected magazine, and an interconnection between said keyboards and said magazines for causing a selected magazine to move to operative position in time with the movement of a selected keyboard.

Signed at Pasadena, Los Angeles County, California, this 28th day of September, 1926.

GEORGE E. MARLATT.
